PROCESS FOR SWEETENING SOUR HYDRO-CARBON OILS

Leslie U. Franklin and Walter H. Weeks, Port Arthur, Tex., assignors to Gulf Oil Corporation, Pittsburgh, Pa., a corporation of Pennsylvania

Application July 12, 1939, Serial No. 284,116

2 Claims. (Cl. 196—29)

Our invention relates to sweetening sour hydrocarbon oils, more particularly light petroleum distillates such as gasolines, naphthas, kerosenes, furnace oils and the like, that is to say, to processes for treating oils of the character indicated, containing "sour" and malodorous sulfur impurities, such as mercaptans, to convert such impurities into sulfur compounds of less objectionable character, whereby the treated oils are rendered sweet to the "doctor" test and free from disagreeable odor.

More particularly, our invention relates to improvements in what is known in the petroleum art as "copper-sweetening," i. e., a process in which sour oil to be treated is contacted with a treating agent comprising a compound or mixture of compounds capable of ionizing to form cupric ions and chloride ions, usually a cupric chloride, with or without the presence of a substantially inert solid carrying agent.

The earliest proponents of copper-sweetening referred, in the main, to two general types of processes, i. e., those in which solutions of copper salts were used as the treating agents, and those in which solid copper salts, frequently distributed on adsorbents such as clay, fuller's earth or the like, were used.

In processes wherein the oil is treated in the liquid phase, it is now generally conceded that sufficient moisture must be present to permit ionization. Naturally, ionization is not a problem in those types of processes in which definite solutions, as distinguished from slurries or solid contact masses are used. However, the solution-type processes involve serious corrosion problems.

For various reasons, the "percolation-type" processes have not proved commercially successful in the treatment of cracked distillates and other oils containing substantial amounts of potential gum- and color-forming constituents. The oxygen stabilities of such oils tend to be seriously reduced after sweetening by this type of process, and the treated oils rapidly develop gum and color upon storage. Nor has this type of process been successful with respect to oils containing relatively high amounts of mercaptans, regardless of whether such oils are cracked or straight-run distillates.

A third type of process, known as the "slurry-type" process, has also been proposed, in which the sour gasoline is mixed with the treating agent in more or less dry form, usually in the presence of a finely-divided adsorbent material, such as fuller's earth, adsorbent clay or the like, and

the sweetened gasoline is finally separated and removed. A limited amount of moisture must be present, but these processes do not give rise to serious corrosion problems; there is no independent aqueous phase.

However, prior art "slurry-type" processes have not resulted in widespread commercial adoption and for the most part have not been successful, except possibly with respect to some oils presenting little or no sweetening difficulties, such as straight-run distillates of low "sourness." In this respect, it should be noted that, especially with respect to cracked distillates, mere sweetening alone is not a criterion of success. It is relatively easy to make most sour distillates sweet to the doctor test; it is quite another thing to accomplish this result at a reasonable cost and without increasing the tendency of the oil to go off in color or to form gums, that is to say without decreasing the oxygen stability of the oil. Copper and copper compounds vastly accelerate oxidation reactions in hydrocarbon oils and processes which leave copper (especially oil-soluble copper) in the treated oils yield unstable and unsatisfactory products. Re-running and further refining of these oils tend to make them sour again.

Our invention has also had for other objects such additional operative advantages and improvements as may hereinafter be found to obtain. Among the objects achieved by our present invention is the provision of a process of copper sweetening in which (1) the sweetening agent is of a substantially non-corrosive type, (2) the sweetening agent can be maintained in a highly efficient condition over considerable operating periods, without substantial losses of the sweetening agent from the system and (3) sweetening is accomplished, even with respect to cracked gasolines and other petroleum distillates having low oxygen stabilities, without adversely affecting the oxygen stabilities of the oils treated.

We have discovered that the aforesaid objects may be achieved, and commercially successful sweetening of sour distillates, including cracked distillates and other unstable petroleum distillates, effected by passing a mixture of (1) the oil to be sweetened, (2) an oxygen-containing gas such as air or oxygen itself, and (3) a solid compound or mixture of compounds capable of ionizing to give cupric ions and chloride ions, (with or without an inert solid carrier) and containing a limited amount of moisture, in substantially concurrent contact through a sweetening zone, then passing the sweetened oil, the oxygen-

containing gas and the treating agent through a second or "stabilizing" zone, wherein regeneration of the treating agent is completed, as indicated by freedom of the sweetened oil from oil-soluble chlorides and oil-soluble mercaptides at the point the oil leaves the stabilizing zone, and thereafter passing the mixture to a separating zone, wherein the solid treating agent is caused to settle by gravity, and from which the treated oil, free of solid treating agent, is withdrawn. The treating agent, in the form of a more concentrated slurry in sweetened oil, is then recycled to the sweetening zone for treatment of fresh quantities of sour distillate. As will be apparent, the process is most advantageously carried out in a continuous fashion, a continuous stream of sour distillate being introduced into the sweetening zone and an equivalent quantity of the sweetened oil being removed from the separating zone.

We have discovered that, in a process of this general type, that is to say, a process in which a flowing stream of oil is treated for the conversion of sour sulfur compounds into sweet sulfur compounds by suspending a solid treating agent of the character indicated in a flowing stream of the sour oil, in the presence of an oxygen-containing gas, sweetening is effected comparatively rapidly, provided the chemical is fresh or has been adequately regenerated, but that at that point along the flow of oil and treating agent where the oil first becomes sweet to the "doctor" test (i. e. where the oil first shows itself free or substantially free from organic mercaptans) the oil tends to contain very substantial quantities of cuprous chloride and cuprous mercaptides. Were the oil to be separated and withdrawn at this point, the separated oil would be of inferior quality due to the highly adverse effect upon oxygen stability and rate of formation of gums and color imparting bodies which is exerted by oil-soluble copper compounds, even when present in extremely small amounts. We have found, however, that if the mixture of oil, oxygen-containing gas and solid treating agent is maintained in contact throughout a stabilizing zone for a considerable period after sweetening has been effected, the reactions which continue for a considerable time after the "sweet" point has been reached will gradually convert cuprous mercaptides and cuprous chloride back into cupric compounds which are insoluble in oil and therefore remain in the mass of solid treating agent maintained in the system instead of being retained in solution in the separated oil.

By maintaining contact of the oil, the oxidizing gas and the solid treating agent throughout the sweetening and stabilizing zones, as aforesaid, the separated oil can be withdrawn from the system without impairment of its oxygen stability. In most cases an actual improvement in oxygen stability is obtained.

It should be noted at this point that these considerations do not necessarily apply to "solution-type" processes, for the reason that cuprous chloride and cuprous mercaptides are quite soluble in the types of solutions commonly employed in such processes. In the latter type of process it is therefore possible to effect regeneration of the sweetening solution out of contact with the oil, the oil being withdrawn from the initial treating zone as soon as it is sweet. Some cuprous compounds may, even in such instance, be retained in the oil but can be removed by "after-treatment" without great difficulty.

In the "slurry" type of process, to which our invention relates, however, there is no independent aqueous phase. For this reason the presence of cuprous compounds simply means that all or a large portion of such cuprous compounds will dissolve in the oil undergoing treatment. They will remain dissolved in the oil unless and until contact is maintained for a considerable period past the point where the oil becomes sweet, as aforesaid.

Probably because of the fact that sweetening and regeneration are to a certain extent concurrent and tend to take place simultaneously to some extent, operators of prior art slurry-type processes have apparently failed to realize the necessity for establishing a further zone wherein the oil, the air and the solid sweetening agent are maintained in contact for a considerable period past the point where sweetening is complete, and prior to separation. It seems to have been assumed that the sweetening and regeneration reactions would be complete at about the same time, whereas in point of fact we have discovered that, under actual operating conditions it takes at least 3 or 4 times as much time to effect regeneration to the point where the oil is substantially free of soluble cuprous chloride and cuprous mercaptides, than it does to effect sweetening of the oil, that is to say, conversion of the organic mercaptides in the oil into organic disulfides or other free sulfur compounds, and this difference is considerably more marked where air, instead of oxygen, is used. And it was not realized that this "stabilization" should take place prior to separation of the oil from the treating material. Therefore, prior art slurry-type copper-sweetening processes have uniformly tended to cause impairment of the treated distillates with respect to their oxygen stabilities and their tendencies toward formation of gums and color-imparting bodies.

It may be observed at this point that attempts have been made in the prior art to overcome this disadvantage by various methods of treating the oil after separation from the sweetening agent, such methods having for their object removal of copper compounds dissolved in the oil. Such after-treatment, when employed for the purpose of removing substantial amounts of cuprous chloride and cuprous mercaptides, does not however represent a satisfactory solution of the problem. There are at least two reasons why this is true. In the first place, removal of the treated distillate as soon as it becomes sweet means that there is a continuous and heavy loss of treating chemicals from the system. The difficulty of removing these compounds tends to increase out of proportion to the amount present in the oil. Consequently such after-treatment, when carried out for the purpose referred to, has meant that in addition to the loss of chemicals from the system, large quantities of after-treating chemicals must be employed. In some instances the amount of cuprous compounds necessary to be removed has been so large that subsequent after-treating methods have not been adequate.

In the second place, any system of the type indicated wherein the oil is removed as soon as it becomes sweet must inherently be inefficient in operation, because of the fact that the solid treating agent tends to subsist in a substantially "spent" or "fouled" condition throughout the system. This vastly increases the difficulty of regeneration.

There is also a third reason which has militated against the success of prior-art processes of the type indicated. This is the fact that, the longer the oil is permitted to retain cuprous compounds in solution, the more difficult will be the subsequent removal of those compounds or their reaction products. Thus, if it is necessary to transfer the oil into a subsequent after-treating stage, some time is necessarily consumed in the transfer of the oil from the treating stage to the after treating stage. In our process, the conversion of cuprous compounds back to oil-insoluble cupric compounds is both prompt and rapid, giving less time for the formation of reaction products, which would be very difficult to remove, especially if they were present in substantial amounts.

In any copper-sweetening process, very small traces of such reaction products are to be encountered, even under the most efficient operating conditions. Even as little as one part of a reaction product between copper and non-sulfur containing constituents of the oil, such as a copper naphthenate, per million parts of oil is deleterious with respect to the stability of the oil; that is to say, even such small traces of materials of the character indicated will cause the oil to deteriorate in storage. In order to remove such slight traces of copper naphthenates and the like (and as a factor of safety against accidental entrainment of the treating agent in the oil leaving the system, although in our process the likelihood of such accidental loss is reduced to a minimum) we usually employ a simple form of after-treatment, of more or less conventional type, as will be set forth hereinbelow. It must not be inferred, however, that the use of such after-treatment implies a lack of success in reaching the objectives of our process. There is a vast difference between the removal of minute traces of copper naphthenates and the like, which is the primary purpose of after-treatment in our process, and the removal of substantial quantities of cuprous chloride and cuprous mercaptides, which has been the primary purpose of after-treatment in prior art processes, especially prior art processes of the "slurry" and "percolation" types.

An inherent advantage of our process, which results in part from the use of concurrent flow and in part from maintenance of a stabilizing zone as aforesaid, is the fact that the treating agent is never allowed to become reduced to too great an extent at any stage in the cycle, thereby vastly facilitating regeneration. We have found that the amount of time of regeneration required by a given amount of copper-sweetening agent increases out of all proportion to the degree to which the agent has previously been reduced by contact with sour oil. Because of our maintenance of the treating agent in a comparatively active condition through the cycle, the tendency for the oil to pick up substantial quantities of soluble cuprous compounds is greatly reduced as compared with prior art processes of the "slurry" and "percolation" types. It may be noted at this point that the unavoidable tendency toward "over-spending" of portions of the treating agent is a serious defect in "percolation-type" processes and also in prior art "slurry-type" processes wherein the considerations underlying our invention have been neglected.

In practicing our invention, the sour oil to be treated, for example a sour cracked gasoline dis-

tillate, previously refined but containing mercaptans, is admixed with a finely divided contact agent in substantially, but not completely, dry form, said agent comprising a compound or mixture of compounds capable of ionizing to give cupric ions and chloride ions, with or without (but preferably with) a substantially inert solid carrying agent.

As disclosed in the prior art, a number of compounds and mixtures of compounds may be employed in preparing the solid sweetening agent; thus cupric chloride ($CuCl_2$) may be used by itself. We have found it preferable, however, to employ a mixture of cupric sulfate and sodium chloride, such mixture being permitted to react in the presence of enough moisture to cause the formation of substantial quantities of cupric chloride. In place of sodium chloride we may use ammonium chloride, and we may expedite the formation of cupric chloride by adding HCl to the mixture. We have found, however, that potassium chloride is less desirable, possibly because cuprous chloride is less soluble in aqueous solutions of KCl than in aqueous solutions of NaCl, NH_4Cl and HCl.

As disclosed in U. S. Patent No. 744,720, the chemicals employed in the sweetening mixture may comprise iron sulfate in addition to cupric sulfate and sodium chloride, the presence of iron sulfate (either ferric, ferrous or both) being beneficial.

Whatever the nature of the chemical or chemical mixture employed, it is preferably combined prior to use with a finely divided inert solid carrying agent. Various types of carrying agents, such as fuller's earth, clays and the like, may be employed, but we have found it highly advantageous to employ a mixture of (1) finely divided asbestos, (2) cupric sulfate and (3) sodium chloride, as set forth and described in the copending application of Leslie U. Franklin, Serial No. 285,636, filed July 20, 1939.

As shown in said application, the use of asbestos as a supporting means for the copper-containing chemical mixture is highly advantageous, as compared with the use of highly adsorbent materials, such as clays, fuller's earth, silica gel and the like. Asbestos, because of its non-adsorbent, yet highly adsorbent character, does not tend to cause polymerization of potential gum-forming constituents—a tendency apt to be exaggerated in effect when copper is also present. Moreover, it does not tend to hold the treating compounds in such a fashion as to prevent or increase the difficulty of regeneration; nor does it tend to make the agent absorb water to too great an extent. Because of its light and buoyant character, it presents an ideally large surface per unit of weight, is easy to suspend in the gasoline and at the same time easy to separate by decantation, which is particularly important in connection with our process. It is also much less abrasive than the highly adsorbent contact agents, such as clay and the like.

It is also preferable that the treating agent be preconditioned and maintained (particularly with respect to moisture content) as set forth, described and claimed in the copending application of Leslie U. Franklin, Walter H. Weeks and Jack W. Harris, Serial No. 284,117, filed concurrently herewith. Such a mixture can be maintained, by proper steps and procedure, in the form of a flocculent or semi-flocculent suspension in the oil, of high sweetening and regenerating efficiency and capable of easy suspension in

and easy removal from the oil undergoing treatment, all as set forth in the aforesaid application Serial No. 284,117. While same moisture is present, the amount is very limited, and an independent aqueous phase is not permitted to exist at any time during the operation.

The oil, carrying the suspended solid treating agent as a slurry, together with oxygen, air or other oxygen-containing gas, is caused to move concurrently through a sweetening zone provided with suitable agitating means for insuring rapidity and intimacy of contact. Regeneration occurs in this zone, but only to a limited extent. After the oil has progressed through this zone only a short distance, in admixture with the treating agent and air, as aforesaid, sweetening is effected; the oil, upon sampling, is sweet to the "doctor" test.

In accordance with our invention, however, we do not remove the oil at this point, but maintain the oil, the oxidizing gas (which may be in solution in the oil) and the solid treating agent in intimate concurrent contact in a stabilizing zone until regeneration of the treating agent is complete, as indicated by freedom of the oil from oil-soluble copper, especially cuprous chloride and cuprous mercaptides. Then, and then only, do we effect separation of the treated oil from the treating agent.

The separation of the treated oil from the treating agent may be effected in various ways, but we prefer to accomplish it by simple continuous decantation, as for example by passing the mixture of oil and air and treating agent to a settling vessel, usually more or less conical in shape and provided with a vertical baffle between the inlet and the treated gasoline outlet. The treating agent settles to the bottom, and is withdrawn and recirculated back to the treating zone.

In most cases, at least a portion of the separating zone serves as a continuation and extension of the stabilizing zone, considerable regeneration taking place in the separating zone in addition to that taking place in the prior zones. This is not objectionable so long as regeneration is completed, to the extent indicated, prior to the point where separation is effected.

By virtue of the concurrent flow and agitation, as well as by virtue of the prolonged contact between the oil and the treating agent in the stabilizing zone of our process, disadvantages inherent in prior processes are avoided. In prior counter-current and percolation-type systems, the least active portion of the treating agent is exposed to contact with the sourest oil. That might be expected, at first glance, to promote efficiency of sweetening and the efficiency of the operation as a whole, but such is not the case. Sweetening itself proceeds so rapidly that it does not require counter-current flow for efficiency. Regeneration, on the other hand, is made far more difficult, because of the fact that the agent tends, at least in part, to be overworked in such a system, and therefore is much harder to regenerate.

Naturally, however, in any system where the opposing reactions (i. e. sweetening and regeneration) go on simultaneously, the chemical acting as a sort of catalyst (in the sense of repeated use and re-use), it is difficult or impossible to measure the degree of "fouling" of the treating agent in exact terms. Stoichiometric amounts of treating agent, with respect to the sour constituents to be removed, may not—and usually are not—required. But it is an inherent

advantage of our process that there is no definite zone in the system where the treating agent is more or less completely fouled, as is likely to be the case in the other types of processes referred to above.

We have found it advantageous to maintain the entire system under a moderate pressure of from, for example, ten to sixty pounds per square inch or even more, in order to maintain air (oxygen) in solution in the oil throughout the system. This use of superatmospheric pressure is especially desirable when operating temperatures, for any reason, are high.

We have also found it advantageous to dry 15 the gasoline or other oil to be treated, prior to introducing it into the system, and also to treat the oil prior to sweetening by means of an alkaline wash, to remove H_2S , even after refining with acid or clay. Usually we maintain the treating agent in a rather dry condition throughout (always free from an independent aqueous phase) but controlled moisture addition may be necessary where conditions are such as to entail loss of water from the total body of treating agent 20 in the system. Maintenance of a suitable moisture content forms a part of the invention disclosed in the aforesaid application Serial No. 284,117.

The regenerated treating agent, after separation and removal from the bulk of the treated oil, but of course still existing as a relatively concentrated slurry in sweetened oil, is withdrawn from the separating zone and returned to the sweetening zone, entering the latter in admixture with, or at a point adjacent to the point of entry of, the sour oil to be treated. It is thus 30 re-used for the treatment of further quantities of sour oil.

From time to time, as necessary, "make-up" 40 quantities of fresh treating agent are added to the system, to replace that mechanically lost during the operation.

The treated oil, after being separated from the sweetening agent, is best passed through a simple after-treating tower, for the purpose of 45 removing any slight traces of oil-soluble copper naphthenate or the like which may be retained in the oil. Such a tower may comprise a vessel adapted to contain a bed of sand impregnated or coated with salt, a cupric compound such as 50 cupric chloride, or a mixture of cupric sulfate and sodium chloride, of low moisture content. Other types of after-treatment may also be employed.

In referring to the fact that in our process the oil, the oxygen-containing gas the solid treating agent are maintained in contact, not merely until the oil has been sweetened but throughout a stabilizing zone until regeneration has been completed, we do not mean to infer that in instances 60 where cupric chloride (either as such as in the form of a reaction product of cupric sulfate and sodium chloride or the like) constitutes the sweetening chemical initially added to the system, regeneration necessarily proceeds to such point as to re-form the cupric chloride initially added. In many instances, there is a certain loss of HCl from the system, due in part to the nature of the reactions taking place, and it is not always 65 possible to supply HCl in such manner as to effectively regenerate cupric chloride as such. We have observed that in many instances after a short operating period the amount of cupric chloride present in the system may fall to a 70 point where detection of $CuCl_2$ is impossible.

Nevertheless, sweetening and regeneration go on, the chemical treating agent being reduced to the cuprous form as a result of the sweetening reactions, and regenerated into some form of cupric compound as a result of the regenerating reactions. Under different conditions, however, the treating agent can sometimes be maintained at a relatively high $CuCl_2$ concentration and HCl may be effectively added to maintain this concentration in spite of losses of HCl from the system. But, whether regeneration actually proceeds to the point of forming substantial quantities of $CuCl_2$, or whether regeneration merely results in the formation of some other cupric compound capable of sweetening, we have found that a sufficient indication of completion of regeneration, for the purpose of determining the proper time of contact of the oil, the oxidizing gas and the solid treating agent in the stabilizing zone, is found in the freedom of the oil from cuprous chloride and cuprous mercaptides. In other words, separation is not effected until the oil, prior to the point of separation, shows itself upon sampling to be free of cuprous chloride and cuprous mercaptides, whether or not the treating agent contains substantial quantities of cupric chloride as such.

While the sweetening, stabilizing and separating steps may be conducted in separate apparatus units, if desired, this is not essential. In the usual instance, we provide two apparatus units or vessels. The first of these units is provided with internal agitating means for insuring turbulent flow, while the second unit, wherein the separation is effected, is usually of larger cross-sectional diameter and is not provided with means for agitating, inasmuch as quiescent flow conditions facilitate settling of the solid treating agent and separation of the final treated oil. With such apparatus, wherein the flow through the first vessel is upward, the lowermost portion of the first vessel constitutes the sweetening zone, while the upper and remaining portions constitute all or a portion of the stabilizing zone, the separating zone being confined to the second vessel. A considerable portion of the stabilization may, however, be effected in the separating zone itself; it is not absolutely essential to complete stabilization before the mixture enters the separating vessel. Stabilization should, however, be complete prior to the point where final separation takes place.

The advantages of our process are demonstrated by the fact that under actual operating conditions over an extended period of time and on a wide variety of sour oils, we have rarely, if ever, decreased the oxygen stability or color of the oil under treatment (and then only when treating exceptionally unstable oils, and to too slight an extent to be serious), and in a majority of cases we have actually improved the oil with respect to oxygen stability, color stability and potential gum-forming tendency. Such results contrast strongly with the fact that the main factor which has hitherto retarded and substantially prevented commercial adoption of copper-sweetening processes of the non-corrosive types for sweetening cracked distillates has been their unfavorable and serious effect upon the quality of the distillates treated.

Operating in accordance with our invention, consumption of chemicals is low, no corrosion problems are encountered, and the system is uniform in operation and not excessive in size or cost.

5 Referring now to the drawing accompanying and forming part of this specification, we now describe, by way of exemplification and illustration, a preferred form in which our invention may be practiced and embodied, but without limiting our invention to the details of this specific form or embodiment, other than in accordance with the claims hereinafter made. In this drawing,

The single figure is a more or less diagrammatic, elevational view of a simple form of apparatus useful in practicing the process of our invention.

10 Hydrocarbon oil to be treated, such for example as a sour cracked gasoline distillate, is first washed with an alkaline solution to remove H_2S , then washed with water to remove traces of the alkaline wash, and finally dried, as for example by passage through a bed or beds of rock salt. 15 These steps, being incidental to rather than a part of our invention, are not illustrated in the drawing.

20 The sour oil then passes through a pipe 1 into the lower part of a treating vessel 2. In the specific instance shown, this vessel 2 comprises a vertically elongated tower divided into a series of super-imposed compartments by means of a series of baffle plates 3, and internally provided with an agitating device 4 driven by a motor 5.

25 The sour oil enters the treating vessel 2 along with a flow of air or other oxygen-containing gas conveniently introduced through a valved conduit 6, and a suitable quantity of treating agent introduced as a relatively concentrated slurry in oil through a pipe 7. Oxygen, air, or other oxygen-containing gas may also be introduced at other points, if desired.

30 Moisture is added to the system, usually in oil solution or suspension, at an appropriate point when and as necessary to replace moisture lost from the chemical; this being especially necessary when the temperatures of the operation, or other conditions, are such as to promote a loss of moisture. Thus moisture (in the form of a 35 solution or suspension in sweet oil) may be added to the system by means of pipe 8.

35 During the upward travel of the mixture of oil and sweetening agent through the tower 2, sweetening and regeneration both take place, the former being completed first. The mixture reaching the top of the tower 2 then passes through a pipe 9 into a separating vessel 10, the upper portion of which is of large horizontal cross-sectional area in comparison with the rate 40 of flow of oil, so as to insure low velocity of flow, and the lower part of which is preferably made in the shape of an inverted cone, as shown. A wier plate 11 and an overflow or offtake pipe 12 maintain a constant level in the vessel 10, and 45 a baffle plate 13, located as shown, prevents liquid introduced through the pipe 9 from passing directly to the overflow wier 11. Preferably, the end of the pipe 9 lying inside the vessel 10 is located below the level established by the wier plate 11.

50 Vents 14 and 15 are provided for the tower 2 and the vessel 10, respectively, these being provided with valves or other devices adapted to maintain whatever pressures are desired.

55 No agitation is provided in the separating vessel, settling and separation being the objects here, rather than contact. The suspension of solid treating agent settles easily, and is withdrawn in the form of a relatively highly concentrated slurry from the bottom of the vessel

10 through a pipe 16 leading to a pump 17, which in turn recirculates the material so withdrawn through the pipe 7 back into the tower 2, for treatment of sour gasoline continuously entering the latter.

By suitably proportioning the size of apparatus and regulating the amount of solid sweetening material in the system, the rate of flow of oil therethrough, and the speed of operation of the pump 17, the solid material can readily be caused to settle out rapidly enough so that the oil leaving the vessel 10 through the pipe 12 contains none of the solid treating agent, or at most insignificant quantities thereof. Naturally, the specific gravity of the sweetening material in comparison to that of the oil, as well as other factors influencing the settling properties of the sweetening material, will have an influence upon the operating conditions maintained to secure this result.

A number of sampling cocks 18 to 23 are provided at various points in the system, those illustrated being located at useful and convenient points. These are important in operating in accordance with our invention, but will of course be realized that changes in the proportions of the apparatus and other conditions may vary the number required, and their location.

A valved inlet 24, communicating with the suction side of the pump 17 is provided for introducing fresh solid sweetening material, as for example in the form of a slurry in previously sweetened oil. A valved offtake pipe 25, on the other side of the pump 17, can be used to withdraw material from the system whenever desired.

As the sweetening reactions occur rapidly, the oil usually shows itself sweet to the "doctor" test by the time it has traversed only a relatively small part of the interior of the tower 2; for example, by the time it reaches the level A—A, which marks the upper limit of the sweetening zone. Experience will show, in any given unit, just where the "sweet" level is when the chemicals are fresh, and it should not be allowed to rise substantially above this level at any time. Thus, if the "sweet" level ordinarily lies below the cock 18, then any sourness in a sample taken at this point (provided the supply of oxygen is adequate and other conditions remain the same) indicates that the addition of fresh treating agent is required, to replace other material lost or rendered inactive in the system. Under proper conditions, this can be reduced to a minimum. At all events, a balance of operating factors should be aimed at.

The mixture then flows through the upper part of the vessel 2, i. e. through the stabilization zone lying above the level A—A, and thence into the separating vessel 10.

Moisture is added to the system, when and as necessary to maintain the desired moisture content of the solid treating agent.

HCl may also be added. At high temperatures tending to cause a loss of HCl, it is sometimes difficult to add enough HCl to maintain a high concentration of CuCl₂ in the system, but, as noted above, it is then possible to operate without HCl addition. At lower operating temperatures, not only is there a reduced tendency toward loss of HCl, but such loss can more easily be replaced, with resultant increase in the amount of CuCl₂ present as such.

When the system is operated without HCl addition, the precise nature of the cupric com-

10 pound formed upon regeneration is perhaps unimportant. It has been suggested that some form of copper oxychloride is formed under such conditions, but it is unnecessary, in so far as our invention is concerned, either to confirm or deny this possibility. We do know that, under proper conditions, operation may be continued successfully for long periods without addition of HCl, even where the CuCl₂ content of the treating agent falls to nil, or at least to a point too low to be determined by ordinary methods.

Even though the presence of considerable quantities of CuCl₂ facilitates sweetening to a considerable extent, it is not necessary to repeatedly withdraw the agent from the system for treatment with HCl or otherwise to replenish its content of CuCl₂, especially where small quantities of CuCl₂ (or a mixture of chemicals containing the same as a reaction product) are added to the system from time to time. These remarks should not be taken to mean that the maintenance of a high CuCl₂ content is in itself disadvantageous; the contrary is probably true so long as this result can be secured without incurring serious disadvantages in other respects. It is not always possible, however, to maintain a high content of CuCl₂ while at the same time maintaining the solid treating agent in a suitable physical condition or "texture."

In any event, when operating in accordance with our invention, as set forth above, the oil, the oxidizing gas and the solid sweetening material are maintained in contact until regeneration and stabilization are completed as far as possible, that is to say until the oil is free or substantially free from cuprous chloride and cuprous mercaptides. Separation should not be effected in any event until the oil contains no more than a slight trace of oil-soluble copper in all forms. It is not essential that this point be reached in the tower 2, for (especially when considerable quantities of air remain dissolved in the oil, as under pressure) substantial regeneration can be effected in the vessel 10. But this point must be reached before the oil leaves the vessel 10, as indicated, for example by a sample withdrawn through the cock 22.

Control of the process, with the above in mind, and in accordance with the other copending applications referred to, is effected by proper regulation of the following factors, in the light of the "degree of sourness" of the oil to be treated:

- (a) Temperature, (normally from 40° to 150 F.),
- (b) Rate of flow of oil,
- (c) Rate of introduction of oxygen, as such or as air or other oxygen-containing gas,
- (d) Amount, physical character, moisture content and sweetening power of treating agent in system,
- (e) Extent of agitation,
- (f) Pressure,
- (g) Addition of fresh treating agent as required by mechanical losses,
- (h) Rate of recirculation of treating agent, and
- (i) Introduction of HCl, (where practiced).

After the oil leaves the vessel 10, it is passed through a stationary bed (not shown) of sand and salt, (with or without cupric chloride), or other material effective to remove traces of copper compounds, such as oil-soluble copper naphthenates and the like. The considerations effecting this step have been discussed hereinabove.

By way of specific examples of our invention,

the following are typical and will serve to show some of the advantages of our process.

Example I

In this example, we treated a sour straight-run gasoline from West Texas crude. Analyses of this gasoline, before and after treatment, respectively were as follows:

	Before treatment	After treatment
Gravity (°API)	62.2	62.0
Color (Saybolt)	+28	+28
Color (Saybolt, after 5 hours exposure to sunlight)	+25	+25
Doctor test	Bad	Good
Copper in gasoline	Nil	Nil
Mercaptan sulfur, percent	0.056	Good
Copper strip test (3 hours at 122° F.)	Good	Good
Oxygen stability, minutes	600+	600+

The oxygen stability of this gasoline is so high that the test is not ordinarily run to completion. If anything, however, the oxygen stability of this gasoline was increased, rather than decreased, by the sweetening operation.

Example II

In this example, the raw gasoline charged to the unit was an acid-treated and re-run cracked gasoline, produced from the same West Texas crude as the straight-run gasoline of Example I. Analyses of the raw gasoline and the treated gasoline were as follows:

	Before treatment	After treatment
Gravity (°API)	58.3	58.2
Color (Saybolt)	+26	+26
Color (Saybolt, after 5 hours exposure to sunlight)	+25	+25
Doctor test	Sour	Sweet
Copper in gasoline	Nil	Nil
Mercaptan sulphur, percent	0.040	Nil
Copper strip test (3 hours at 122° F.)	Good	Good
Oxygen stability, minutes	580	750

The marked increase in oxygen stability is especially to be noted.

Both of the examples given above represent characteristic results obtained in large-scale operations, conducted over extended periods of time. These operations were conducted under substantially the same conditions in each case, as follows:

The gasoline was first washed with an aqueous caustic soda solution and then dried, as set forth above.

The solid treating agent was prepared by mixing the following ingredients in the following proportions:

	Pounds
Powdered CuSO ₄ ·5H ₂ O	208
Powdered NaCl	625
Asbestos (Johns-Manville Co. No. 7-RF asbestos floats)	167

The mixture thus prepared was allowed to age and react for 48 hours, in the presence of a slight amount of added moisture (about 1 per cent). After aging, the material was placed in the system in the presence of previously sweetened gasoline, and the mixture was agitated at a tem-

perature of from 130° to 145° F. for about five hours, until the moisture content was considerably reduced, i. e. to 2 per cent. Air was introduced during this period.

The sweetening operation was then started, some gasoline being fed into the system continuously at a temperature of 135° F. and at the rate of 50 bbls. per hour, until the moisture content of the solid treating agent was reduced to 0.75 per cent. The charging rate was then increased to 100 bbls. of gasoline per hour, and moisture was introduced in such amount as to maintain the moisture content of the treating agent substantially constant. A gauge pressure of 30 lbs. per square inch was maintained throughout, and air was continuously introduced at the rate of approximately 5 cubic feet (measured at 60° F. and 14.7 lbs. per square inch) per barrel of distillate charged. Fresh treating agent was added from time to time.

In the claims hereinafter made, the term "oxygen" is intended to denote not merely pure oxygen itself, but also oxygen as existing in air or other oxygen-containing gas.

While we have set forth and described our invention hereinabove with reference to numerous operating details (some of which are in accordance with inventions disclosed in the other co-pending applications referred to herein), and with reference to specific operating examples, our invention may be variously practiced and embodied within the scope of the claims hereinafter made.

What we claim is:

1. In a process for sweetening sour oil by means of a solid and substantially dry treating agent comprising a solid substance capable of ionizing to give cupric ions and chloride ions, maintaining a continuous cyclic flow of said solid agent in suspension in oil through a sweetening zone, a stabilizing zone, and a separating zone, continuously introducing sour oil and oxygen into said sweetening zone, and continuously separating and removing treated oil from the cycle at a point where the oil in the cycle is sweet and free from oil-soluble cuprous chloride and cuprous mercaptides.

2. The process of sweetening sour hydrocarbon oil containing mercaptans which comprises passing a mixture of said oil, oxygen, a solid substance capable of ionizing to give cupric ions and chloride ions, together with a substantially inert solid carrier and water in an amount insufficient to produce a separate aqueous phase, through a sweetening and regenerating zone wherein the mixture is intimately commingled to simultaneously sweeten the oil and effect partial regeneration of the treating agent, thereafter subjecting the mixture to continued intimate contact in an enlarged stabilizing zone for a sufficient period of time to effect substantially complete regeneration of the treating agent in the presence of the sweetened oil, and then separating and removing treated oil from the treating agent at a point where the treated oil is free from soluble cuprous chloride and cuprous mercaptides.
